UNITED STATES PATENT OFFICE.

WALTER WERNER, OF HOOSICK FALLS, NEW YORK, ASSIGNOR TO THE NOBLE & WOOD MACHINE CO., OF HOOSICK FALLS, NEW YORK, A CORPORATION OF NEW YORK.

BEATER ROLL.

Application filed April 28, 1925. Serial No. 26,538.

To all whom it may concern:

Be it known that I, WALTER WERNER, a citizen of the United States, residing at Hoosick Falls, in the county of Rensselaer 5 and State of New York, have invented certain new and useful Improvements in Beater Rolls, of which the following is a specification.

This invention relates to beater rolls for 10 beating engines, and particularly to the formation of the heater-bar and the bar-receiving recesses in the roll heads into which the bars are inserted and locked by means of locking wedges, so as to form what are 15 known as bandless rolls.

In order to produce a satisfactorily secure attachment of the beater bars to the heads of the rolls, and to insure proper alignment of the bars when locked in place, it has been 20 the quite general practice to machine a part or all of the bar-receiving recesses in the roll heads in order that the recesses in one head might coincide exactly with the recesses in the other, so that when the bars are 25 locked in place therein they will lie in exact alignment. The proper alignment of the beater bars is very desirable, and in practice it has heretofore been found to be extremely difficult to obtain the desired alignment of the bars when unfinished cast bar- 30 receiving recesses were used, due to the various causes which contribute toward inaccuracies in heavy castings such as are used to make the roll heads.

The object of this invention is to make 35 feasible the use of cast bar-receiving recesses without the necessity of finishing the same, and at the same time make possible the proper aligning of the bars and the securing 40 of the same in place by means of wedges, regardless of such inaccuracies in the heads as cannot be overcome by ordinary careful moulding of the same, and to make feasible the substantially perfect alignment of the 45 bars in both the horizontal and vertical planes without the necessity of machine work on the heads other than the boring for the shaft and the turning of the rims thereof.

I accomplish my objects by making use 50 of peculiarly shaped beater bars, bar-receiving recesses, and locking wedges, and by inserting the wedges at a point which lies between a pair of accurately surfaced

spaced bearing points formed by the turning of the rim of the head of the roll.

My improvements are clearly shown in the accompanying drawings, in which:

Fig. 1 is a longitudinal section through one side of a head of my improved beater 60 roll, one end of the beater bar being secured in place therein.

Fig. 2 is a plan view of a portion of one head with portions of some of the beater bars in place therein.

Fig. 3 is an elevation of Fig. 2.

Fig. 4 is a cross section along the line 4-4 on Fig. 2.

The same reference characters refer to the same parts throughout the several views.

Referring to the drawings, A represents a roll head, R the cast bar receiving recesses, B the beater bar; and WR, WL, the right and left hand locking wedges.

My improved beater bar is rolled to exact 75 form from any suitable material, usually steel, and preferably has a cross section substantially as illustrated. Lengthwise of each side of the bar B are formed spaced parallel ribs bt and bb; the ribs bb lying 80 along the lower or inner edge of the bar, that edge of which is adapted to seat against a finished annular shoulder or ledge A², on the head A, when the under side of the rib bt is seated against the finished surface A² of the rim of the head. The ends of the bar may be notched out (on the lower side) up to the ribs bt, leaving an overhang adapted to contact with the surface of the roll head rim which lies 85 outside of the end of the recess, R.

The bar-receiving recesses in the head have a cross-section substantially as illustrated in the drawings. The bottom of the recesses are substantially flat and rectangular in 95 plan and lie below the level of the top of the annular ledge A³; the side walls retreat for most of their height so that the recesses flare toward both the top and side entrances thereto, the upper portions of the 100 side walls drawing toward each other so that side ledges A⁴ are formed along the top entrance, the under side of said ledges tapering up and towards the side entrance to the recess. The under sides of the ledges A⁴ 105 are adapted to contact with the upper side or edge of the locking wedges when they are driven to place.

The locking wedges are made of a malleable metal, usually malleable iron, and are substantially triangular in shape (the thin edge being squared off) tapering from the 5 top toward the bottom, and from the head toward the point, decreasing in both width and thickness as the point is neared. The side of the wedge which is adapted to lie against the side of the beater bar B is a 10 plain surface, while the opposite side thereof is slightly irregular the taper of the wedge being more abrupt near the point. At the head end of this irregular shaped side is a side projecting cross rib W, between 15 which rib and the inner face of the rim of the head a pointed tool may be driven so as to loosen the wedge when it is desired to withdraw it for the purpose of freeing the bar so that it may be removed from the roll. 20 The bars having been lowered into the bar receiving recesses in the roll head, are locked in place by driving a wedge along each side thereof. The bottom of the wedges contacting with the upper side of the ribs bb, the 25 tops with the tapered under side of the ledges A⁴. Should the pair of bar-receiving recesses of the pair of heads not lie in exact alignment, the beater bar may still be locked in alignment by driving one wedge 30 further than the other, or by using wedges of unequal thickness and if necessary reversing the position of the thick and thin wedges at the other end of the bar.

By forming the ribs bt along the sides of 35 the beater bar at a point in its width where the under side of them will contact with the accurate surface A² when the bottom edge of the bar contacts with the accurate surface A³, I provide support for the bar across 40 the whole of the rim of the head and so prevent the driving of the locking wedges from drawing down the ends of the bars and causing the centers to arch, as at times happens with some present types of roll construction. 45

The usual shaft, intermediate bar supports, and wood filler strips are to be used in this roll.

In this improved beater roll the beater 50 bars are securely and detachably held accurately in place without the necessity of finishing the bar-receiving recesses in the heads. The only machining which is actually necessary is the boring for the shaft and the 55 turning of the surfaces A² and A³, the rolls being thus very inexpensive to produce and no loss of accurate alignment of the bars is experienced, for by using a wedge on each side of the bar I am able to compensate for 60 any inaccuracies in the alignment of the

cast recesses which cannot be eliminated by ordinary careful casting. In addition, I have insured the bars against arching due to the drawing power of the locking wedges.

I claim:

1. In a beater roll: the combination of a pair of heads mounted on a shaft, each head having a ledge formed on the inner side thereof and below its rim, and a series of bar-receiving recesses spaced about its circumference the side walls of said recesses flaring apart toward both the top and side openings thereto but drawing toward each other at the top to form abutments which restrict the width of the top opening; beater 70 bars fitting loosely in said recesses and having a rib formed along each side at the lower edge thereof, and a rib parallel to said first mentioned ribs and adapted to contact with the top of the rim of the head 75 when the bottom edge of said bar is in contact with the top side of said ledge; and a pair of locking wedges one on each side of said bar and co-acting therewith to lock same against lateral displacement, the top of 80 one of said wedges contacting with the under side of one of said abutments and the lower side of said wedge contacting with the upper side of one of the ribs along the lower edge 85 of said bar so that the driving of the wedge 90 will force said bar to a seat and lock it against vertical displacement.

2. A head for a beater roll, having an annular ledge formed on the inner side 95 thereof, a series of circumferentially spaced bar-receiving recesses formed in and opening through the top and inner side of said rim, the bottom of said recesses lying below the top of said ledge, the side walls of said recesses flaring apart as they approach both 100 the top and side openings thereto the tops thereof drawing toward each other and forming a pair of rib-like abutments which restrict the top opening to the recess and the 105 under sides of which taper upwardly as the end opening is approached.

3. A beater bar for a beater roll comprising: a bar of metal having a longitudinal rib formed on each side thereof and adapted to contact with the surface of the 110 rim of the roll head when the bar is in place therein and the bottom edge of the bar is against its seat, the inner half of said bar tapered from said rib toward the inner edge 115 of the bar and having a rib formed along said inner edge on each side of said bar.

In testimony whereof I have affixed my signature.

WALTER WERNER.
